FEED GRINDER

Filed Jan. 29, 1929

UNITED STATES PATENT OFFICE

CHARLES D. AMMON AND ELMER W. WILCOX, OF LINCOLN, NEBRASKA; SAID WILCOX
ASSIGNOR TO SAID AMMON

FEED GRINDER

Application filed January 29, 1929. Serial No. 335,918.

Our invention relates to feed grinders and to mills in general and more specifically to the structure for supporting the screens within the mill.

5 The primary object of our invention is the provision of means whereby the screen will be securely latched in place in the mill and whereby it may be conveniently and easily inserted in the mill or withdrawn therefrom 10 or replaced by another screen.

Another object of our invention is to provide a yielding pressure foot for the door of the feed opening so as to hold the door in position under the vibration of the machine.

15 Having in view these objects and others which will be pointed out in the following description, we will now refer to the drawings, in which

Figure 1 is a median vertical sectional view 20 of the entire feed grinder and showing specifically the screen in its latched position and showing also the pressure foot bearing against the closure.

Figure 2 is a vertical sectional view 25 through a portion of the back wall of the feed grinder showing the rear connection of the screen with the back wall.

Figure 3 is a view similar to Figure 2 but showing the relationship of parts at the forward extremity of the screen in its relation 30 to the front wall and to the screen opening when the screen is being forced into position.

Figure 4 is a view in front elevation of 35 the closure for the screen opening of the feed grinder.

The feed grinder shown in our drawings is of the hammermill type with a shaft 10 adapted for a speed of about 3000 R. P. M. 40 Secured to this shaft are pivoted hammers 11 which extend in radial direction when the grinder is in operation. The casing is provided with a front opening 12 through which the feed is introduced. The feed coming 45 through the opening 12 falls against the ham-

mers 11 which crush the feed in mid air due to the rapid movement of the hammers 11. The crushed and partly crushed feed is hurled against the anvils 13' and 13'' and against the screen 14. The impact of the 50 partly crushed feed against the anvils results in a further crushing of the feed and this crushing process is repeated between the hammers 11 and the anvil 13 until the feed has been reduced to the proper size. When 55 the particles are sufficiently fine they are hurled out through the screen 14 from whence they fall to the bottom of the casing where they may be removed.

In the operation of feed grinders of this 60 type it is frequently necessary to replace screens. This necessity arises from the fact that the grinder is used largely on farms where many different kinds of feed are ground ranging all the way from cornstalks 65 to small grains. This, of course, necessitates the use of screens having openings of various sizes. To a less extent replacement becomes necessary when a screen has been seriously damaged from constant wear or otherwise. 70 Our invention has to do largely with facilitating the easy replacement of screens.

As in other grinders of this type, the screen 75 is in the form of a cylindrical arc and it rests on a plurality of transverse rods or bars 15. The front and rear end edges of the screen are usually latched. In prior constructions the screen is usually removed through an opening in the side of the casing. The arrangement is cumbersome and difficult 80 to operate and it requires considerable time and labor to remove or insert a screen. A further drawback to the old type of screen removing arrangements is the fact that the side opening seriously weakens the casing 85 which thus becomes hammered to pieces under the vibrations generated within a high speed machine. We obviate these difficulties by preserving the full strength of the side walls of the grinder which carry the bear- 90

ings for the shaft and further by the use of very simple clamping devices which operate automatically at the end edges of the screen.

In carrying out our invention, we provide the front wall with an opening as best shown in Figure 3. A hinged closure 16 is provided for tightly closing this opening when the grinder is in use. When the closure 16 is fully closed the forward edge of the screen 14 will rest against the edge of the front wall of the casing at the top of the opening and bearing against the anvil 13'. In other words, the screen is clamped at its forward edge between the anvil 13' and the closure 16 with its upper edge tightly clamped and in tangential relation with the front wall. The rear edge of the screen is also tightly clamped between an anvil 13'' and the rear wall of the casing. The anvil 13'' is secured to the rear wall by means of a bolt 17 passing through the rear wall and through the spacing block 18 and through the anvil 13''. For facilitating the removal of the screen through the front opening, the rear wall of the casing is provided with an aperture 19 of ample size for introducing a screw driver or similar tool. The edge of the spacing block is beveled as shown in Figure 2 so that any suitable tool may engage the rear edge 30 of the screen 14 for prying the screen loose from its rear connection. This loosening of the screen should be done with the door 16 open and the movement of the screen 14 will be sufficient to force the forward edge of the screen through the opening. The screen may then be easily withdrawn through the front opening.

The clamp for the forward edge of the screen is best shown in Figure 3 taken in connection with Figure 4. The closure 16 is provided with a pivot shaft 20, the ends of which are journalled in ears 21 projecting forwardly from the side edges of the casing. The middle portion of the upper edge 40 of the closure is cut away as best shown in Figure 4. Two substantially L-shaped guides 22 project from the forward edge of the casing, one of their functions being to guide the movements of the closure 16. The forwardly projecting portions of the guides 22 are rounded as shown in Figure 3 so that the edge of the closure will ride on the rounded surfaces of the guides 22. The forward edge of the screen 14 also contacts with the guide 22 and it rides into position against the rounded surfaces of the guides 22. It will be apparent from an inspection of Figure 3 that the closing of the closure 16 will involve considerable leverage against the forward edge of the screen 16 to force it not only into position against the anvil 13' but to also exert a force in the curvilinear direction along the screen to force the rear end of the screen into the latching position shown in Figure 2.

The arrangement for inserting or withdrawing a screen is simplicity itself. For inserting the screen, the screen is simply shoved in by hand against very little resistance until the rear latch is reached. At that time the forward edge of the screen is sufficiently near the curved surfaces of the guide members 22 for the closure 16 to engage that edge and to force it along the guide surfaces until it is seated against the anvil 13'. At this point in the movement the rear edge of the screen is fully latched, and as the forward edge of the screen leaves the curved surfaces of the guides 22, the resiliency of the screen snaps it into position with the upper edge of the screen contacting with the sectioned edge of the front wall. The closure 16 may then be latched by means of the latches 23 and tightened by means of the thumb nuts engaging the latches. The steps are simply reversed when it is desired to remove the screen. The closure 16 is first opened and the forward edge of the screen is then released so that it bears against the curved surfaces of the guide members 22. A suitable tool is then inserted through the aperture 19 to pry loose the rear edge of the screen from the rear clamp. This forces the forward edge of the screen forwardly and it may then be removed with very little effort by hand or by the use of a pair of pliers.

The feed opening 12 is provided with a slidable closure 24. Under the vibration of a high speed machine of this character, the tendency of the closure 24 is to fall and to thus close the opening 12. A fixed pressure against the rear of the closure 24 is not adapted for preventing the falling of the closure due to the vibration of the machine. We have therefore provided a pressure foot for maintaining a constant pressure against the closure 24 and we have further added structure for adjusting this pressure. As shown in Figure 1, a collar member 25 is secured to the top wall of the casing and slidable in the collar is a rod 26 having a head 27, the head being preferably made of wood or similar material. The end of the rod 26 carries one or more notches and a coil spring surrounds the rod and extends from the head 27 to the nuts. It is apparent that the compression of the spring may be varied by tightening or loosening the nuts on the rod 26.

Having thus described our invention in such full, clear, and exact terms that its construction and operation will be readily understood by others skilled in the art to which it pertains, what we claim as new and desire to secure by Letters Patent of the United States is:

1. A grinder including a comminutor and a screen within a casing, said casing being provided with an opening for the insertion and withdrawal of said screen, and a hinged closure for the opening of said casing, said

closure being adapted to exert a leverage action on said screen during the closing movement thereof.

2. A grinder including a comminutor and a screen within a casing, said casing being provided with an opening for the insertion and withdrawal of said screen, means on said casing for releasably engaging the edge of said screen remote from the opening, and a hinged closure for the opening of said casing, said closure being adapted to exert a leverage action on said screen during the closing movement thereof to force the edge of said screen into engagement with said means.

3. A grinder including a comminutor and a screen within a casing, said casing being provided with an opening for the insertion and withdrawal of said screen, and a hinged closure for the opening of said casing, said closure being adapted to exert a leverage action on said screen during the closing movement thereof and having a clamping action with a portion of said comminutor for engaging an edge portion of said screen therebetween when said closure is in closed position.

4. A grinder including a comminutor and a screen within a casing, said casing being provided with an opening for the insertion and withdrawal of said screen, means on said casing for releasably engaging the edge of said screen remote from the opening, and a hinged closure for the opening of said casing, said closure being adapted to exert a leverage action on said screen during the closing movement thereof to force the edge of said screen into engagement with said means, said casing being provided with an aperture adjacent said clamping means for the insertion of a pry for releasing said screen from engagement with said means.

5. A grinder including a comminutor and a screen within a casing, said screen having substantially the form of a semicylindrical surface, said casing being provided with an opening adjacent one of the straight edges of said screen for the insertion and withdrawal of said screen, said screen being movable in the direction of its length, and a closure hingedly secured to said casing and adapted to close the opening therein, said closure being adapted to exert a leverage action on said screen during the closing movement thereof.

6. A grinder including a comminutor and a screen within a casing, said screen having substantially the form of a semicylindrical surface, said comminutor including a pair of anvils secured in spaced away relation to said casing at the end edges of said screen and including also a rotatable beater having its axis of rotation at the cylindrical axis of said screen, said casing being provided with an opening adjacent one of said anvils for the

insertion and removal of said screen, and a hinged closure for said opening, said closure being adapted during closing movement to exert a leverage action on said screen for seating the edge of said screen and being adapted when closed to exert a clamping action toward one of said anvils with the edge portion of said screen clamped therebetween.

In testimony whereof we affix our signatures.

CHARLES D. AMMON.
ELMER W. WILCOX.
